US00D765625S

(12) **United States Design Patent** (10) **Patent No.:** **US D765,625 S**
(45) **Date of Patent:** **** Sep. 6, 2016**

- (54) **BATTERY FOR AN ELECTRONIC DEVICE**
(71) Applicant: **Apple Inc.**, Cupertino, CA (US)
(72) Inventors: **Jody Akana**, San Francisco, CA (US); **Bartley K. Andre**, Palo Alto, CA (US); **John B. Ardisana, II**, San Francisco, CA (US); **Jeremy Bataillou**, San Francisco, CA (US); **Sawyer Isaac Cohen**, Sunnyvale, CA (US); **Daniel J. Coster**, San Francisco, CA (US); **Ruchir Dave**, San Jose, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **David A. Pakula**, San Francisco, CA (US); **Scott P. Porter**, Cupertino, CA (US); **Matthew Dean Rohrbach**, San Francisco, CA (US); **Peter Russell-Clarke**, San Francisco, CA (US); **Ashutosh Y. Shukla**, Santa Clara, CA (US); **Jason Sloey**, Cedar Park, TX (US); **Ian Spraggs**, San Francisco, CA (US); **Christopher J. Stringer**, Woodside, CA (US); **Tang Yew Tan**, San Francisco, CA (US); **Eugene Antony Whang**, San Francisco, CA (US); **Michael Benjamin Wittenberg**, Sunnyvale, CA (US); **Charles B. Woodhull**, San Francisco, CA (US); **Rico Zörkendörfer**, San Francisco, CA (US)
(73) Assignee: **Apple Inc.**, Cupertino, CA (US)
(***) Term: **14 Years**
(21) Appl. No.: **29/510,611**
(22) Filed: **Dec. 1, 2014**
(63) Continuation of application No. 29/431,725, filed on Sep. 10, 2012, now Pat. No. Des. 718,753.
(51) **LOC (10) Cl.** **14-03**

(57) **CLAIM**

The ornamental design for a battery for an electronic device, as shown and described.

DESCRIPTION

FIG. 1 is a bottom front perspective view of a battery for an electronic device showing the claimed design;

FIG. 2 is a front view thereof;

FIG. 3 is a left side view thereof;

FIG. 4 is a right side view thereof; and,

FIG. 5 is a bottom view thereof.

The broken lines in the figures show portions of the battery for an electronic device that form no part of the claimed design.

1 Claim, 4 Drawing Sheets
